UNITED STATES PATENT OFFICE

1,969,568

ROLL-HOLDER FOR RIVET SPINNING
MACHINES

George A. Linley, Trumbull, Conn.

Application September 17, 1931, Serial No. 563,305

5 Claims. (Cl. 78—46)

The present invention relates to roll-holders for rivet spinning machines, and has for an object to provide a roll-holder which will reliably support the rolls against strain and wear, and which may be readily adjusted to insure a proper relation of the rolls at all times. The roll-holder is of a type in which a pair of rolls are rotatably held in a holder at a slight angle, with their concave peripheral surfaces meeting at the bottom, where they engage and form the rivet head, and are separated at the top. Due to wear or strain, there has been a tendency in the past for the rolls to become separated after very little use, with the result that a small bur would be formed at the center of the rivet head, and in order to obviate this condition it is proposed in the present invention to provide a holder in which the roll-supporting axle may be adjusted with respect to the side arms of the holder to any desired extent, the side arms adapted to be drawn into the exact proper close relation with the rolls, and in which the axle is so formed as to be held against loosening under the severe strain to which the device is put in use.

25 A further object is to provide a roll-holder which will automatically lubricate the rolls so that a small amount of lubricant will be supplied to each rivet head as it is spun down.

30 A still further object is to provide a roll-holder which will protect the operator against flying chips, flakes and lubricant.

With the above and other objects in view embodiments of my invention are shown in the accompanying drawing, and these embodiments 35 will be hereinafter more fully described with reference thereto and the invention will be finally pointed out in the claims.

In the drawing:

40 Fig. 1 is a front elevation of a roll holder, according to one embodiment of the invention.

Fig. 2 is a side elevation thereof.

Fig. 3 is a vertical sectional view, taken along the line 3—3 of Fig. 1.

Fig. 4 is a perspective view of the guard employed.

Fig. 5 is a perspective view of the axle employed.

Fig. 6 is a vertical sectional view of modified form of the invention.

Fig. 7 is a fragmentary side elevation thereof, 50 the guard being removed.

Similar reference characters indicate corresponding parts throughout the several figures of the drawing.

Referring to the drawing, the roll-holder is 55 of substantially cylindrical shape, and is pro-

vided at its upper end with the usual hexagonal flange 10 for securing the same to the threaded shank of the spinning machine, an interiorly threaded socket 11 being provided in the upper end of the holder for this purpose. A pair of 60 downwardly extending spaced arms or jaws 12 and 13 are provided between which the rolls rotate, the inner walls of these arms being flat and slightly converging downwardly, so that the opening between the rolls is slightly wider at the top than at the bottom. This opening is divided at the top by a downwardly projecting fin 14, the sides of which are tapered in parallel relation to the inner converging sides of the arms, and is adapted to separate the rolls at the top, 70 as will presently more fully appear.

The arm 13 is provided with a shouldered passage 15, while the arm 12 is provided in opposed relation with a threaded passage 16, and the arms are tempered, so that they have 75 a slight resiliency.

The rolls 17, 18 which are of the usual form, are rotatably mounted on a pin or axle 19, having a head 20 at one end, and having a threaded portion 21 at the other end, split or slotted transversely, as at 22, the pin being tempered and the threads 21 slightly oversize with respect to the threaded passage 16, so that it will engage said passage under compression. The threads 21 of the pin are of such length that when engaged with the threaded passage 21 they extend 80 for a distance inwardly of the inner wall of the arm 13.

The pin 19 is engaged through the shouldered passage 15 and screwed into the threaded passage 16, and due to the compression of the split end of the pin under spring tension is securely held against loosening in any desired position of adjustment. The length of the threads 20 permits the pin to be tightened to any desired 90 extent to draw the arms 12 and 13 toward each other to maintain a tight relation of the rolls at their point of contact, the pin being held against loosening in this relation both by its own tension and the tension of the arms. In the usual type of roll-holder the pin is shouldered adjacent the screw threads, this shoulder abutting the inner wall of the arm into which the pin is screwed, so that when it is tightly 95 screwed into place the relation of the arms is 105 fixed and no adjustment for wear is possible. According to my invention the pin may be tightened to any desired extent, so that regardless of wear the rolls may be maintained in their proper relation and their period of use 110

is extended. The formation of burs on the rivet heads due to separation of the rolls is obviated.

In the upper portion of the holder there is provided a drilled hole 23 which extends downwardly from the threaded socket 11 to a point within the fin 14 below the peripheries of the rolls, and within this hole there is provided a lubricating wick 24 pressed downwardly into contact with the roll surfaces by a spring 25 disposed in the hole between the upper end of the wick and a retaining closure plate 26, which may be snapped into place and held by the threads. Oil or grease is supplied to the wick through a radial duct 27 in the holder, the outer end of which is adapted to be normally closed by one side of the guard member, presently to be described. As the rolls revolve in opposite directions a film of oil or grease will be constantly supplied to their surfaces by the wick, and this will be transmitted to the rivet head. The rotation of the rolls in opposite directions will tend to turn the wick about a vertical axis, so that it will not become unevenly worn.

The guard member is of U-shape, its side portions 28 and 29, which are adapted to conform to the side of the holder, being connected at the bottom by transverse portions 30 and 31. Due to the springiness of the metal of which the guard is preferably formed the side portions 28 and 29 may be sprung outwardly and when engaged with the holder will cling to it under tension. The lower end of the guard has an opening 32 through which the rolls project, and at each side is bulged out, as at 33 and 34, to provide clearance at the sides for the rolls. The guard is retained in place upon the holder by spring lugs 35 and 36 at its upper edge, which snap into recesses 37 and 38 formed in the sides of the holder, and which permit the guard to be readily removed and replaced when desired. It will be observed that the guard forms a closure for the oil duct 27. In operation the guard prevents oil from flying on the operator, and also confines any chips or flakes which may be carried from the rivet head upon the roll surfaces, so that the danger of being hit in the eye by such particles is obviated.

In Figs. 6 and 7 I have illustrated a modification in which the drilled hole 23 is of larger diameter than in the first form and does not extend into the fin, and a narrower slot 39 is provided in the fin, preferably by drilling, and forms a bearing in which the shaft 40 of a pair of lubricating rollers 41 and 42 is engaged for vertical sliding movement. The rollers which are disposed at each side of the fin beneath the wick 24 have slightly rounded peripheries and ride on the surfaces of the rolls 17 and 18, being freely rotatable upon the shaft 40, so that they rotate in opposite directions during rotation of the rolls 17 and 18 and carry lubricant from the wick to the surfaces of said rolls.

In the modification illustrated in Figs. 6 and 7 I have also shown a modified form of roll supporting pin 19, which it will be understood may also be employed in the first embodiment, if desired. In the split end of the pin a tapered threaded hole 43 is drilled and is engaged by a tapered set screw 44, which is adapted to be screwed into the pin after it is adjusted to expand and bind the threaded end of the pin against movement, this tapered set screw being withdrawn when it is desired to turn the pin.

I have illustrated and described preferred and satisfactory embodiments of my invention but it

will be obvious that changes may be made therein, within the spirit and scope thereof, as defined in the appended claims.

Having thus described my invention, what I claim and desire to secure by Letters Patent is:—

1. In a roll-holder for rivet spinning machines, a holder body having a pair of spaced arms having aligned pin receiving passages, one of said passages being threaded, a pin extending through the other of said passages and screwed into said threaded passages, rolls carried upon said pin between said arms, the upper portion of said holder having a vertical passage therein and a duct extending from said passage to the exterior surface of said holder, lubricating means disposed in said passage and engaging the surface of said rolls, and a removable guard disposed about said spaced arms and forming a lateral closure for said rolls and also forming a closure for said duct.

2. In a roll-holder for rivet spinning machines, a holder body having a pair of spaced arms having aligned pin receiving passages, one of said passages being threaded, a pin extending through the other of said passages and screwed into said threaded passage, said pin having a split in its threaded end and adapted to expand against said threaded passage to bind the pin against turning, rolls carried upon said pin between said arms, and a guard disposed about said spaced arms forming a lateral closure for said rolls and having open portions exposing the ends of said pin.

3. In a roll holder for rivet spinning machines, a holder body comprising an upper head portion and a pair of downwardly extending arms having upwardly diverging opposed walls, a roll carrying pin extending between said arms, a pair of apertured rolls disposed upon said pin between said walls and having bearing contact therewith, and having bearing contact with each other at the rivet spinning point outwardly of said arms, a separating fin extending downwardly from said head portion and disposed in the central vertical plane between said rolls adapted to maintain them in diverging relation parallel to said diverging walls, said head portion and said fin having a common central passage of greater width than the thickness of said fin extending downwardly through said head portion and into said separating fin and forming a slot in said fin, and lubricating means disposed in said passage and slot and engaging the surfaces of said rolls at each side of said fin.

4. In a roll holder for rivet spinning machines, a holder body comprising an upper head portion and a pair of downwardly extending arms having upwardly diverging opposed walls, a roll carrying pin extending between said arms, a pair of apertured rolls disposed upon said pin between said walls and having bearing contact therewith, and having bearing contact with each other at the rivet spinning point outwardly of said arms, a separating fin extending downwardly from said head portion and disposed in the central vertical plane between said rolls adapted to maintain them in diverging relation parallel to said diverging walls, said head portion and said fin having a common central passage of greater width than the thickness of said fin extending downwardly through said head portion and into said separating fin and forming a slot in said fin, and a lubricating wick disposed in said passage and slot and engaging the surfaces of said rolls at each side of said fin, the walls of said slot abutting said wick at opposed sides in the central vertical plane between said rolls to hold said wick against

distortion through the rotating pressure of said rolls.

5. In a roll holder for rivet spinning machines, a holder body comprising an upper head portion and a pair of downwardly extending arms having upwardly diverging opposed walls, a roll carrying pin extending between said arms, a pair of apertured rolls disposed upon said pin between said walls and having bearing contact therewith, and having bearing contact with each other at the rivet spinning point outwardly of said arms, a separating fin extending downwardly from said

head portion and disposed in the central vertical plane between said rolls adapted to maintain them in diverging relation parallel to said diverging walls, said head portion having a lubricant passage of greater width than the thickness of said fin extending downwardly therein, and lubricating rollers mounted at each side of said fin and engaging the surfaces of said rolls, and having their peripheries in relation to said passages to receive lubricant therefrom.
